TELEPHONE SYSTEM

William J. Muldoon, Hempstead, and Harold T. Stenhammer, New York, N. Y., assignors to Control Instrument Company, Inc., Brooklyn, N. Y., a corporation of New York

Application June 5, 1943, Serial No. 489,748

18 Claims. (Cl. 179—18)

This invention relates to improvements in telephone systems and has particular reference to a full automatic inter-communicating system.

An object of the invention is to provide an improved and simplified system wherein the use of relays individual to each subscriber's line is eliminated by having a line finder switch individual to each trunk circuit employed, which finder, upon preselection of its trunk circuit in preparation for receiving a call to be initiated at any one of these subscribers' stations, is operated until its wipers engage the terminals of a line at which a calling condition exists, whereupon the finder connects the calling line to said trunk circuit, and switching means common to the various trunk circuits is then activated to preselect another and idle trunk and its associated finder for use in establishing a connection for a succeeding call.

Another object is to provide a system wherein a line finder in a trunk circuit is made common to a plurality of subscribers' lines and provided in said circuit with improved means to control its line hunting operation and seizure of a line upon which a calling condition exists.

A further object is to provide a trunk circuit with a line finder common to a plurality of calling lines, which finder has a normal position from which it is moved in a hunting operation by a relay, also in said trunk circuit, which is energized when said trunk circuit is taken for use, and which is thereafter controlled to restore said finder to its normal position at the conclusion of a call.

The inventive idea involved is capable of receiving a variety of expressions a preferred one of which is shown in the accompanying drawings; but it is to be expressly understood that said drawings are employed merely for the purpose of illustrating the invention as a whole and not to define the limits thereof, reference being had to the appended claims for this purpose.

In the drawings:

Figs. 1 and 2, when arranged side by side in vertical position, illustrate diagrammatically a system embodying the features of the present invention, the dotted lines extending between various parts of the apparatus indicating mechanical drive connections therefor.

As illustrated in the drawings, the trunk circuit is in the condition existing at the moment of its preselection resulting from a call previously made over another trunk, and is so preselected for the purpose of handling the next call to be initiated, for example, at the sub-

scriber's station A which desires a connection to station B over the talking line conductor 100 of said preselected trunk. In accordance with the present invention, immediately upon the preselection of the circuit herein shown by the trunk selector or allotter switch T. S., its associated rotary line finder L. F. is started from a normal position to seek the terminals of a subscriber's line on which a call will be subsequently initiated. The finder continues its hunting operation until one of its wipers encounters a terminal of a calling line, such as A, whereupon the finder stops and the selector switch T. S. immediately operates, assuming at least one of the other trunks serving the system is idle, to preselect the latter trunk for use with a call initiated subsequently to that at station A. If all trunks are busy at the moment, switch T. S. awaits an idle condition on one of them before starting its preselecting operation. Upon receiving a dialing tone at station A, series of impulses are transmitted to a two-motion selector switch S. S. (Fig. 2) and, assuming the station B being called to be idle, a ringing signal is operated at said station, and the removal of the telephone threat from its switch hook completes the connection to station A.

The hunting operation of the line finder L. F. individual to the trunk circuit shown, is started at the moment when the trunk is preselected. Thus, when the wiper 102 of the trunk selector T. S. engages the terminal 103 of the present trunk having battery potential thereon, indicating the idle condition of the trunk, a circuit is established from ground at the trunk selector relay 104, which is slow-release, through the winding of said relay, wiper 102 and terminal 103, conductor 105, winding of finder control relay 106, conductor 107, uppermost back contact of slow-release relay 108, and lower back contact of low-impedance relay 109 to battery. Relays 104 and 106 energize and the operation of the former relay prevents further energization of the slow-release stepping magnet 110 of the trunk selector T. S., which would otherwise operate over a circuit extending from ground through the self-interrupted switch 111, winding of magnet 110, conductor 112, the lower-most back contact of relay 108, conductor 113, and the contact of relay 104 to battery. However, since said back contact is now open, said circuit is not established and the wiper 102 of the trunk selector remains on the terminal until the trunk selector is again operated to preselect another idle trunk, as will later appear.

The energization of the relay 106 in the previously described circuit, closes another circuit for operating the motor 114 that drives the shaft of the line finder L. F. on which is mounted the wipers 115 and 116 of said switch. The circuit for thus operating the motor 114 extends from the negative side of battery 117, the back contact of the slow-release, high-impedance relay 118, motor 114, and the lower front contact of relay 106 to the positive side of battery. The rotary wipers 115, 116 are started from their normal positions and continue to rotate until the wiper 116 encounters a potential on one of its terminals indicative of a calling condition on a subscriber's line which shall be assumed to be at station A, the subscriber theretofore having now removed the receiver from its switch hook. When this occurs, ground is connected to the impulse sender at the station and also to one side of the receiver thereat, the other side being connected through the capacitor to the terminal 128 of the line finder and the terminal 239 of the selector switch S. S. Terminal 129 of the line finder and terminal 240 of said selector are also electrically connected and are joined to the impulse sender of the calling line through the resistor 121. When the line finder is in its normal position, a switch 119 thereof, in series with a resistance 120, is open; but this switch closes when the wipers of the finder start rotating from their normal positions and periodically opens each time said wipers complete a revolution and pass over said positions. During the closure of said switch 119, it connects ground to the conductor 105 through said resistance 120 for the purpose of controlling the restoration of the line finder to normal at the conclusion of the call, as will later appear. It is also noted that the impedance of relay 118 is approximately seven times greater than that of relay 109 and, due to this, said impedance diminishes the current surge and reduces, to a point below the audible range, the inductive coupling occasioned by the line finder wipers passing over the terminals of a busy line during the hunting operation.

In said hunting operation of the line finder, it is evident that the wipers thereof may engage terminals of one or more busy calling lines each connected to a busy trunk. Under such circumstances, it becomes necessary to prevent energization of relays 109 and 118 of the trunk associated with said line finder and to also avoid the release of relay 109 of the busy trunk. This is accomplished by the high and low resistances of said relays and a series line resistance in the busy calling line. Thus, when the wipers of the finder of the preselected trunk pass over the terminals of a busy line, relays 109 and 118, in series, of said trunk are momentarily in parallel with the relay 109 of the busy trunk. This latter relay is in series with the busy station line resistance and is the only one of the two relays 109 and 118 of the busy trunk that is energized, as will presently appear. The parallel condition of relays 109 and 118 of the preselected trunk with relay 109 of the busy trunk does not, however, result in the release of the latter relay 109 since the total resistance of relays 109 and 118 of the preselected trunk is several times greater than that of the relay 109 of the busy trunk so that the voltage drop in the latter relay, due to shunting, is not sufficient to cause it to release. On the other hand, the high resistance relay 118 is adjusted to operate only on the higher voltage existing across it when in series connection with the low resistance

relay 109 and the line resistance 121, this condition developing nearly full voltage across relay 118. Therefore, relay 109 will only operate after relay 118 and since, in the parallel condition, voltage across relays 118 and 109 of the preselected trunk is that of relay 109 of a busy trunk and since this voltage is low due to the drop in the line resistance 121, relay 118 of the preselected trunk will not operate and the wipers of the line finder of said trunk will pass over the busy line terminals.

The call at station A now having been initiated, as previously stated, when the wiper 116 of the line finder engages the terminal individual to said line, voltage is applied to relays 109 and 118 which, at this time, are not in parallel with relay 109 of a busy trunk, and a circuit is now established extending from battery through the windings of relays 109 and 118, the upper front contact of the now energized relay 106, wiper 116 and the terminal engaged thereby, resistor 121, and through the impulse sender and upper contact of switch hook at station A, to ground. The greater voltage drop across the high resistance relay 118 will cause this relay to energize and thereby, at its back contact, open the operating circuit for the motor 114, and said motor then stops with the wipers 115 and 116 of the line finder engaged with the terminals individual to the calling line. Although the relay 109 is in series with the energizing circuit of the relay 118, it will not energize until relay 118 has operated, at which time the latter relay short circuits itself through the conductor 122 and its front contact. This action raises the voltage sufficiently to cause energization of relay 109 through the front contact of relay 118, and when relay 109 operates it temporarily opens, at its lower back contact, the energizing circuit for relays 104 and 106, and establishes a circuit from ground through the winding of relay 108, and through the middle front contact of relay 109 to battery. Relay 108 energizes and, at its upper back contact, permanently breaks said energizing circuit for relays 104 and 106, causing the latter to remain in released condition until the call is terminated.

A dial tone is now impressed upon the subscriber's line at station A extending from ground through the source 200, conductor 201, the closed contacts 202 of the selector switch S. S., conductor 203, the lower back contact of relay 106, conductor 123, the back contact of relay 204, conductor 205, the upper back contact of slow-release relay 206, wiper 115 of the line finder, conductor 124, and through the condenser and receiver at station A.

Before describing the operation of the selector switch S. S. resulting from the transmission of impulses from the calling station, the preselection of another idle trunk for taking care of a succeeding call will be set forth. This preselection by the switch T. S. occurs the instant the line finder seizes the terminals of the calling station A and the relay 104 of the trunk selector releases as a result of this seizure. Assuming that at least one of the other trunks serving the system is idle at this time, the release of relay 104 connects battery thereat to the contact of said relay from whence a circuit extends over the conductor 125, similar to conductor 113 of the present trunk and leading to an idle trunk, the lower back contact of relay 108 of said idle trunk, the conductor 126 connected to the latter, which corresponds to the conductor 112, the winding of stepping magnet

110, and its interrupter 111 to ground. Magnet 110 is energized, causing its wiper 102 to engage terminal 127 individual to another trunk. If this trunk is busy, relay 108 thereof will be energized, and therefore no circuit will be established through its upper back contact to operate relay 104 which is then in series with relay 106 of the busy trunk. Consequently, stepping magnet 110 will continue to find battery on the back contact of relay 104 and will be operated again to rotate wiper 102 to the next trunk terminal. Should this trunk be idle, relay 104 of the trunk selector will be energized in series with the relay 106 of the idle trunk over the previously described circuit through the upper and lower back contacts, respectively, of relays 108 and 109 of said trunk, and the trunk selector wiper will then stop on the terminal of the idle trunk, thus pre-selecting the same for a succeeding call. As heretofore set forth, the preselection of the idle trunk initiates the operation of the line finder associated with said trunk. From the foregoing, it will be apparent that if all trunks should be busy at any given moment, all of the relays 108 thereof will be energized and, as a consequence, the energizing circuit for the stepping magnet 110 will be open at the lower back contacts of all said relays 108 and the trunk selector will remain inoperative until one of said back contacts is closed by the release of the associated relay 108 at the termination of a call over the trunk in which said relay is located. Then, the trunk selector operates, as described, to find and preselect the trunk which has become idle.

Returning now to the condition where the subscriber at station A receives the dial tone, the impulse sender at said station is now operated by the subscriber to send impulses over the signalling circuit to operate the selector switch S. S. to establish a connection to the called line B. At this time, relays 108 and 109 are energized, and relay 108, being slow to release, does not de-energize during transmission of the impulses. The first and succeeding impulses, if any, of the series corresponding to the tens digit of the called line causes the successive release and operation of relay 109, and the first release of said relay results in the establishment of an energizing circuit for relay 206 extending from ground through the winding of said relay, lower front contact of relay 108, and the upper back contact of relay 109 to battery. Since relay 206 is slow to release, it remains energized during transmission of the first series of impulses and then releases at the conclusion thereof. In response to the first impulse transmitted, relay 109 releases and is again operated, and upon its operation, a circuit is established for the vertical stepping magnet 207 of the selector S. S. extending from ground through the winding of magnet 207, the upper closed contact of the contact bank or pile 208, the front contact 209 of relay 206 and the upper front contact of relay 109 to battery. The energization of magnet 207 in response to the closure of said circuit operates its armature and stepping pawl to move the shaft 210 of the selector S. S. vertically one step, and each successive impulse, should there be more than one in the first series, causes the magnet 207 to be similarly operated to impart further vertical movement to the shaft 210 until the wipers 211 and 212 carried by said shaft are associated with the horizontal row of terminals of the switch bank in which the line being called is located. At the first vertical stepping operation of magnet 207, 75

the cam 213, controlled by the shaft 210, operates to open the contacts 202 of the contact pile 214 and close the remaining contacts therein, the opening of contacts 202 disconnecting the dial tone from the calling line.

Upon completion of the transmission of the first series of impulses, corresponding to the tens digit of the called line, relay 206 releases, the circuit therefor being now broken at the upper back contact of relay 109 which now remains energized awaiting the transmission of the second series of impulses corresponding to the unit digit of the called line. When relay 206 releases and before the second series of impulses is started, the horizontal or rotary stepping magnet 215 of the selector switch S. S. is operated over a circuit extending from ground through the winding of said magnet, the now closed contacts 216 of the contact pile 214, the lower closed contacts 217 of the contact pile 208, the back contact 218 of relay 206, and the upper front contact of relay 109 to battery. Energization of the magnet 215 in this circuit causes shaft 210 of the selector switch to rotate one step, thereby operating the cam 219 to open the contacts 217 in the contact pile 208 and reverse the positions of the other contacts in said pile in preparation for receiving the second series of impulses. The opening of the contacts 217 by the cam 219 breaks the above described energizing circuit for magnet 215.

The second series of impulses is now transmitted from the calling station and relay 109 responds to these impulses as before. Upon first deenergization of relay 109, relay 206 is again energized, as previously described, and when the front contact 209 of said relay is closed and relay 109 is again energized, an operating circuit for magnet 215 is established extending from ground through the winding of said magnet, contacts 216 of the pile 214, contacts 220 of the pile 208, the front contact 209 of relay 206, and the upper front contact of relay 109 to battery. Magnet 215 thus operates in response to the second series of impulses to rotate the shaft 210 of the selector switch so that the wipers 211 and 212 are also rotated horizontally to engage with the terminals of the called line in accordance with the number of impulses transmitted in said second series.

It will first be assumed that the called station B is idle, in which event relay 206, after a slight interval, releases at the conclusion of the second series of impulses. However, while relay 206 is still energized, a circuit is established for relay 204 extending from ground through the winding thereof, and the closed contacts 221 of relay 206 to battery. Relay 204 energizes and is thereupon locked in a circuit through its winding and lower front contact, the upper front contact of relay 108 and the lower back contact of relay 222 to battery. After this locking circuit has been established, relay 206 then releases. Energization of relay 204 connects a ringing voltage to the called line over the circuit extending from battery through the interrupter cam 223, the upper front contact of relay 204, back contact 224 of relay 206, upper back contact of relay 222, wiper 212 of the switch S. S. and the engaged terminal 225, to ground through the ringer and lower switch hook contact at station B. A portion of this ringing voltage is fed back to the receiver of the calling line through the resistor 226, upper back contact of relay 206, and line finder wiper 115 to the condenser and receiver at station A. Removal of the receiver at the called station

in response to the ringing signal, closes a path for energizing relay 222 which extends from ground at the upper contact of the switch hook, the impulse sender at said station, resistor 221, terminal 228 and wiper 211 engaged thereby, winding of relay 222 and the lower front contact of relay 109 to battery. Energization of relay 222 disconnects the ringing circuit from the interrupter cam 223 to the ringer at station B and also opens, at its lower back contact, the holding circuit for relay 204 which thereupon releases. A talking connection between the calling and called lines is now established, over the trunk conductor 100 through the wipers 115 and 212 of the line finder and selector switches, respectively, and the upper back contacts of relays 204 and 206.

If the called line happens to be busy when wipers 211 and 212 of the selector switch S. S. engage the terminals of said line, relay 222 will be energized in the previously described circuit therefor, since the pull-in voltage of this relay is low enough to cause it to operate even when paralleled by the relay 109 of the trunk connected to the busy called station. Relay 206, instead of releasing because of the idle condition of line B, will now be locked in a circuit extending from ground through the winding of said relay, its lower front contact, and the lower front contact of relay 222 to battery. A busy signal now will be connected to the calling line from the source 200 through the interrupter cam 229, upper front contacts of relays 222 and 206, and from thence over the conductor 100 and line finder wiper 115 to the receiver at station A.

The release of the trunk and its associated equipment is under the control of the calling subscriber so that the replacement of his receiver on the switch hook, either upon receiving a busy signal or at the termination of a call, has the effect of restoring the trunk circuit to its idle condition. When the receiver is replaced, ground at the calling station is removed from the terminal engaged by wiper 116 and relay 109 thereupon releases, causing the release of relays 108 and 222. In the case where the called line was busy, relay 206 was energized in a holding circuit by relay 222 and therefor restoration of the latter relay opens said holding circuit for relay 206, which then also releases. Upon release of relay 108, a circuit is established for the finder control relay 106 extending from ground through the switch 119 of the line finder, which is then in its closed or off-normal position, resistor 120, winding of relay 106, upper back contact of relay 108, and lower back contact of relay 109 to battery. As previously described, energization of relay 106 causes the operation of motor 114 and the wipers of the line finder switch are then rotated until their normal positions are reached, whereupon switch 119 is mechanically opened, breaking the circuit of relay 106 and thus bringing the line finder to rest at its normal position, with relay 106 released.

The restoration of selector switch S. S. also occurs when relays 108 and 109 are released. A circuit is thereupon closed extending from ground through the winding of horizontal release relay 230, contact 231 of the pile 214, contact 232 of the pile 208, contact 233 of the pile 214, the middle back contact of relay 108 and the upper back contact of relay 109 to battery. Relay 230 energizes to release the holding pawl 234 from its ratchet 235 and the shaft 210 of the selector switch is then rotated counterclockwise by a re-

storing spring (not shown) to likewise turn the wipers 211 and 212 so that they become disengaged from the terminals of the called line. When shaft 210 has returned to its normal horizontal or rotative position, it restores cam 213 so that the position of the contacts in the pile 208 are again reversed. Upon closure of the contact 236 in the pile 208, an energizing circuit is established for the vertical release relay 237 through said contact 236, contact 233 of pile 214, the middle back contact of relay 108 and upper back contact of relay 109 to battery. Relay 237, upon energizing, releases the holding pawl 233 from engagement with the shaft 210 and the latter then moves downwardly to its normal position and upon reaching the same, operates the cam 213 to permit the contact pile 214 to also restore to normal. The circuits for the release relays 230 and 237 are now opened and said relays are de-energized. The trunk circuit is now restored to an idle condition and ready to be preselected for another call.

What is claimed is:

1. In a telephone system, calling and called subscribers' lines, a plurality of trunk circuits, line finders each individual to one of said trunk circuits, means to operate the line finder of one trunk to seek a calling line, a trunk selector responsive to the seizure of said calling line by said finder for preselecting another trunk and its finder and to start the latter on a hunting operation for a succeeding call before said call is initiated, and means thereupon operable to connect said calling and called lines over the first named trunk.

2. In a telephone system, calling and called subscribers' lines, a plurality of trunk circuits, line finders each individual to one of said trunk circuits, means to operate the line finder of one trunk to seek a calling line, means in the latter trunk to prevent the line finder thereof from seizing another calling line connected to a busy trunk, a trunk selector responsive to the seizure of the first named calling line by said finder for preselecting another trunk for a succeeding call, and impulse responsive means operable to connect said calling and called subscribers' lines.

3. In a telephone system, calling and called subscribers' lines, a resistance in each calling line, a plurality of trunk circuits, line finders each individual to one of said trunk circuits, means to operate the line finder of one trunk circuit to seek a calling line, means including variations in resistances in said trunk circuit and the resistance in a previously busy calling line cooperating to prevent said seeking finder from seizing said busy calling line, and impulse responsive means operable, after seizure of the first named calling line by said line finder, to connect the latter line to said called line.

4. In a telephone system, calling and called subscribers' lines, a resistance in each calling line, a plurality of trunk circuits, line finders each individual to one of said trunk circuits, means to operate the line finder of one trunk circuit to seek a calling line, a high resistance relay in said trunk circuit responsive to a calling condition of said calling line to stop said finder on the terminals of said line, a low resistance relay in series with said high resistance relay, said high resistance relay, when in series with the line resistance of a previously busy calling line, preventing the seizure by said finder of said busy calling line, and impulse responsive switching means to connect the first named calling and called lines.

5. In a telephone system, calling and called subscribers' lines, a line resistance in each calling line, a plurality of trunk circuits, line finders each individual to one of said trunk circuits, means to operate the line finder of one trunk to seek a calling line, a high resistance relay in said trunk responsive to a calling condition of said calling line to stop said finder on the terminals of said line, a low resistance relay in series with said relay operable to hold said calling line, said high resistance relay, when in series with the line resistance of a previously busy calling line, preventing the seizure by said finder of said busy calling line switching means operable upon seizure of the first named calling line by said finder to preselect another trunk for a succeeding call, and switching means thereafter responsive to impulses transmitted from said first named calling line to connect the same to a called line.

6. In a telephone system, calling and called subscribers' lines, a plurality of trunk circuits, a line finder individual to each of them, switching means operable upon seizure of a calling line by a finder of one of said trunk circuits to preselect an idle trunk for a succeeding call, means responsive to the selection of said idle trunk to initiate the operation of the finder associated therewith before said succeeding call is initiated, and means to complete the connection from the first named calling line to a called line.

7. In a telephone system, calling and called subscribers' lines, a plurality of trunk circuits, a line finder individual to each of them, switching means common to said plurality of trunks and operable upon seizure of a calling line by one of said finders to preselect an idle trunk for a succeeding call, means responsive to the selection of said idle trunk to initiate the operation of the finder associated therewith before said succeeding call is initiated, and other switching means responsive to impulses transmitted from the first named calling line to connect the latter to a called line.

8. In a telephone system, calling and called subscribers' lines, a plurality of trunk circuits, a line finder individual to each trunk and having a normal position, means to preselect one of said trunk circuits for connection to said calling line prior to the initiation of a call on said line, means responsive to such preselection for starting the operation of the associated line finder from its normal position to seek the call to be initiated, means operable upon seizure of said calling line, after said call is initiated, to actuate said trunk preselecting means to select another trunk for a succeeding call, and means to thereupon complete the connection from said calling line to said called line over the first named trunk.

9. In a telephone system, calling and called subscribers' lines, a plurality of trunk circuits, a line finder individual to each trunk and having a normal position, means to preselect one of said trunk circuits for connection to said calling line prior to the initiation of a call on said line, means responsive to such preselection for starting the operation of the associated line finder from its normal position to seek the call to be initiated, means operable upon seizure of said calling line, after said call is initiated, to actuate said trunk preselecting means to select another trunk for a succeeding call, means to thereupon complete the connection from said calling line to said called line over the first named trunk, and means to restore said line finder to its normal position

upon conclusion of the call by the calling subscriber.

10. In a telephone system, calling and called subscribers' lines, a plurality of trunk circuits, a line finder individual to each of them, switching means common to said trunks and operable upon seizure of a calling line by one of said finders to preselect an idle trunk for a succeeding call, means to prevent operation of said switching means should all said trunks be busy, means to initiate said preselecting operation when one of said trunks becomes idle, means responsive to the selection of said idle trunk to initiate the operation of the finder associated therewith before initiation of said succeeding call, and impulse responsive means for connecting said calling line to said called line.

11. In a telephone system, calling and called subscribers' lines, a plurality of trunk circuits, a line finder individual to each of them, a rotary trunk selector common to said trunks and actuated upon seizure of a calling line by the finder of one of said trunks, to preselect an idle trunk for a succeeding call, means to prevent said trunk selector from operating should all of said trunks be busy, means to initiate the operation of said selector, when one of said trunks becomes idle, to preselect said trunk, means effective upon completion of said selection to start operation of the finder of the latter trunk before initiation of said succeeding call, and means to complete the connection between said calling and called lines over the first named trunk.

12. In a telephone system, calling and called subscribers' lines, trunk circuits serving said lines, means to preselect one of said circuits for use by a subsequently initiated call, a line finder, means responsive to the preselection of said circuit to start a hunting operation by said finder and to continue such operation until a call is initiated on a calling line, means to thereupon stop said finder on the terminals of said calling line, and means to connect said calling line to a called line.

13. In a telephone system, calling and called subscribers' lines, trunk circuits serving said lines, means to preselect one of said circuits for use by a subsequently initiated call, a line finder, means responsive to the preselection of said circuit to start a hunting operation by said finder and to continue such operation until a call is initiated on a calling line, means to thereupon stop said finder on the terminals of said calling line, means responsive to the seizure of the calling line by said finder to again operate said circuit preselecting means, and means to complete the connection between said calling line and a called line.

14. In a telephone system, calling and called subscribers' lines, trunk circuits serving said lines, means to preselect one of said circuits for use by a subsequently initiated call, a line finder having a normal position, means responsive to the preselection of said circuit to start said finder from its normal position in search of a call to be subsequently initiated and to continue such hunting operation until such call is made, means to thereupon stop said finder on the terminals of the calling line, means to complete said call to a called line, and means to restore said finder to normal at the conclusion of said call.

15. In a telephone system, calling and called subscribers' lines, trunk circuits serving said lines, means to preselect one of said circuits for use by a subsequently initiated call, a line finder

having a normal position, means responsive to the preselection of said circuit to start said finder from its normal position in search of a call to be subsequently initiated and to continue such hunting operation until such call is made, means to thereupon stop said finder on the terminals of the calling line, means responsive to the seizure of the calling line by said finder to again operate said circuit preselecting means, means to complete the connection from said calling line to a called line, and means to restore said finder to normal at the conclusion of said call.

16. In a telephone system, calling and called subscribers' lines, a plurality of trunk circuits, line finders each individual to one of said trunk circuits, means to operate a line finder of one trunk to seek a calling line, means in the latter trunk to prevent the line finder thereof from seizing another calling line connected to a busy trunk, a trunk selector responsive to the seizure of the first named calling line by said finder for preselecting another trunk for a succeeding call, means responsive to the preselection of said other trunk to immediately start its associated finder on a hunting operation without awaiting initiation of said succeeding call, and means to connect said calling line to a called line.

17. In a telephone system, calling and called subscribers' lines, a resistance in each calling line, a plurality of trunk circuits, line finders each individual to one of said trunk circuits, means to

operate the line finder of one trunk circuit to seek a calling line, means including variations in resistances in said trunk circuit and the resistance in a previously busy calling line cooperating to prevent said seeking finder from seizing said busy calling line, means to stop said finder on the terminals of the first named calling line, means responsive to such seizure to preselect an idle trunk circuit for a succeeding call, means operable upon such preselection to start a hunting operation of the finder associated with said idle trunk without awaiting initiation of said succeeding call, and means to connect said first named calling line to a called line.

18. In a telephone system, calling subscribers' lines, a resistance in each line, a trunk circuit, a finder for connecting a calling line through said circuit to a called line, a high resistance relay in said trunk circuit responsive to a calling condition on said calling line to stop said finder on the terminals of the latter line, a low resistance relay in series with said high resistance relay, the latter relay, when in series with the line resistance of a previously busy calling line, preventing seizure of said busy line by said finder and means operable through said trunk circuit to connect said calling line to a called line after seizure of the former by said finder.
